UNITED STATES PATENT OFFICE

DONATO VACCARO, OF CLEVELAND, OHIO

WINDOW SHADE BRACKET

Application filed July 30, 1930. Serial No. 471,765.

This invention relates to improvements in supporting brackets of a type designed for the accommodation of shade rollers, curtain rods and the like.

8 One of the principal objects of the invention consists in the assemblage of the different types of supports as a unitary structure whereby shade rollers and curtain rods will be uniformly positioned.

10 More specifically stated the bracket construction is provided with attaching portions constructed and arranged in such manner as to obviate distortion of the assemblage.

15 With the above and other objects in view, the invention further consists of the following novel features and details of construction, to be hereinafter more fully described, illustrated in the accompanying drawing and pointed out in the appended claims.

In the drawings:

Figure 1 is a fragmentary elevation of a window frame showing the present invention applied.

25 Figure 2 is a top plan view thereof.

Figure 3 is a perspective view of one of the brackets.

30 Figure 4 is a perspective view of a locking element for a curtain rod upon the bracket.

Figure 5 is an enlarged detail sectional view taken through the bracket and locking means for a curtain rod.

35 Referring to the drawings in detail wherein like characters of reference denote corresponding parts, the reference characters 10 indicate the standards of complementary supporting brackets having portions 11 offset adjacent their uppermost ends to overlie the upper edges of a window frame in the manner suggested in Figure 2 of the drawings. Openings 12 and 13 are also arranged at intervals in the standards for the accommodation of screws or other fastenings whereby the brackets will be rigidly maintained in position for use. Each of the complementary standards are provided with outwardly and forwardly projecting ears 14 having slots or openings for the accommodation of the conventional forms of shade roller trunnions.

Ears 15, laterally and outwardly projecting from the sides of each of the standards, are provided with openings 16 for the accommodation of fastening elements 17. The attaching portions 18 for the telescopically associated sections 19 of a curtain rod are also provided with openings for the accommodation of the fastening elements 17. Locking plates 20 overlying the attaching portions 18 for the curtain rod are provided with notches 60 or cut-out portions 21 to facilitate accommodation of appropriate portions of the curtain rod whereby the fastening elements may be accommodated in the manner suggested in Figure 5. It is to be noted from the foregoing description and accompanying drawing that the anchorages for the attaching ends for the curtain rod are of rigid character in order that the heavier forms of curtains, drapes or portieres may be suspended 65 therefrom.

The principle of rigidity preserved throughout, in the construction and application of the invention, will serve to sustain and maintain shade rollers and curtain rods 75 in their respective positions in a manner uniformly correct to avoid interference in the operation of either the curtain or shade.

The invention is susceptible of various changes in its form, proportions and minor 80 details of construction and the right is herein reserved to make such changes as properly fall within the scope of the appended claim.

Having described the invention, what is 85 claimed is:

A curtain rod support provided with an ear disposed for abutting engagement with the attaching end of the curtain rod, a locking plate removably positioned upon the ear 90 and attaching end of the rod and having a cut-out portion to accommodate an appropriate portion of the rod, and fastening means adapted to extend through the ear, end of the rod and the locking plate. 95

In testimony whereof I affix my signature.
DONATO VACCARO.
